SHOE FASTENER

Minas Yartyan, New York, N. Y.

Application March 6, 1933. Serial No. 659,889

10 Claims. (Cl. 36—50)

This invention relates to means for fastening a shoe and other foot covering on the foot of the wearer.

Some of the objects of the present invention are: to provide a novel and improved fastener of the indicated character whereby the shoe may be quickly and easily fastened and unfastened; a fastener which is simple and inexpensive, and neat as applied to the shoe; and one which embodies substantial and efficient features of construction.

The nature of the invention and its distinguishing features and advantages will appear when the following specification is read in connection with the accompanying drawing, in which

Figure 1 is a plan view of a shoe having a fastener constructed in accordance with the invention applied thereto, the parts thereof being unfastened;

Fig. 2 is an enlarged section taken approximately on the line 2—2 of Fig. 1;

Fig. 3 is a view similar to Fig. 2, showing the parts fastened;

Fig. 4 is a view of the spring and latch hook assembly;

Fig. 5 is a plan view of the eye member as it appears before being applied;

Fig. 6 is a transverse section on the line 6—6 of Fig. 5.

Referring now more particularly to the drawing, it will be apparent that there has been shown, by way of example, a shoe 10 of the oxford type the upper 11 of which is split or divided to provide the usual opening to allow a person to readily slip the foot into the shoe before fastening the same, and also to allow the foot to be easily withdrawn from the shoe after it is unfastened.

The shoe upper 11 has attached thereto the usual tongue 12 for closing the opening at the front hereinbefore referred to. In accordance with the invention, there is provided means on the upper 11, which co-operates or is engageable with means on the tongue 12 for fastening the shoe after the foot has been slipped into the same and which may be disengaged to unfasten the shoe so that it may be removed. The said means on the upper 11 of the shoe in the present instance, includes a piece of spring wire which is bent upon itself to provide members 14 which are suitably joined so as to be flexed toward and away from each other. In other words, there is provided a resilient and flexible element or spring substantially of V shape. The said spring is secured in place on the upper 11 by means of a strip, or a plurality of strips 15, of leather or

other suitable material, secured to the inside of the upper 11 to form a pocket in which the spring is disposed and concealed. It will be apparent that the members 14 will be disposed respectively, at opposite sides of the split or opening in the upper 11. The said means on the upper, in addition to the spring, includes latch members or hooks 16, one of which is arranged on each of the members 14, so as to have pivotal movement thereon. The upper 11 of the shoe is cut away in order that each latch member or hook 16 may be disposed to the outside with the bill 17 of the hook disposed beyond the edge of the upper, as shown most clearly in Fig. 2.

The means on the tongue 12 which co-operates with the spring members 14 and the latch members or hooks 17, consists of a piece of metal developed to provide a body for a plurality of alternate openings 18 and transverse members 19, and attaching portions 20. The openings 18 and members 19 constitute eyes. The prongs or attaching portions 20 are made so as to be bent or clinched in engagement with the tongue 12, as at 21, so as to retain or secure the members 19 disposed on the outside of the tongue 12. The members 19 are bowed upwardly, as shown most clearly in Fig. 6, so that the hooks may be readily engaged therewith. It will be apparent that by providing a plurality of openings 18 and members 19, it will be possible to obtain adjustment of the upper 11 according to the size of the wearer's instep, since the hooks 16 may be selectively engaged with the members 19 according to the size of the instep of the wearer's foot.

From the foregoing it will be apparent that with the hooks 16 disengaged, as shown in Fig. 2, a person may readily slip the foot into the shoe, after which by a simple manipulation with both hands of the adjacent portions of the upper in which the spring members 14 are disposed, the bills 17 of the hooks 16 may be engaged, respectively, with certain of the members 19. This engagement of the hooks is subject to the flexing of the members 14, which will react when released to retain the hooks 16 engaged with the members 19, and thus fasten the shoe on the foot of the wearer. When it is desired to unfasten the shoe to remove the same, it is only necessary to exert pressure with the hands on the adjacent portions of the upper 11, whereupon the bills of the hooks 16 may be disengaged and the foot readily withdrawn from the shoe.

It will be obvious, and it is to be understood, that it is within the present invention to employ latch members or hooks without the use of a

spring, in which case the latch members or hooks will be secured or pivotally connected directly with the material of the shoe upper. It will also be obvious that separate eyes may be used and applied to the tongue 12 in lieu of the single piece of material from which the transverse members 19 are developed.

What I claim is:

1. In a shoe fastener, the combination with the 10 shoe upper and tongue, of cooperative latching members on the upper and tongue respectively, said members on the upper being engageable with the member on the tongue to fasten the shoe on the foot, and means on the upper to retain said members engaged as aforesaid.

2. In combination in a shoe fastener, a substantially V-shaped spring secured to the shoe at the front opening therein, a tongue in said opening, latch members pivotally connected with the 20 side portions of said spring, and eye members secured to the tongue, said latch members being engageable with said eye members and being retained so engaged by said spring, to fasten the shoe on the foot of the wearer.

3. In a shoe fastener, the combination with the 25 shoe upper and tongue, of cooperative latching members on the upper and tongue respectively, said members on the upper being engageable with the member on the tongue to fasten the shoe on the foot, and resilient means on the upper to retain said members engaged as aforesaid.

4. In a shoe fastener, the combination with the 30 shoe upper and tongue, of cooperative latching members on the upper and tongue respectively, said members on the upper being engageable with the member on the tongue to fasten the shoe on the foot, and a spring wire secured to said upper along the front opening at the tongue to retain said members engaged as aforesaid.

5. In combination in a shoe fastener, a spring 35 wire secured to the upper of the shoe in a pocket formed therein along the front opening at the tongue of the shoe, hooks pivotally connected with said wire at opposite sides of said opening respectively, and means on said tongue which may be engaged by said hooks subject to the flexure of said wire to retain said hooks engaged with said means to fasten said shoe on the foot of the wearer.

6. In combination in a shoe fastener, hooks carried by the shoe upper at opposite sides of the 40 opening therein which is closed by the tongue thereof, and a member having a series of spaced

upwardly-bowed portions secured to said tongue, said portions being selectively engageable by said hooks to fasten the shoe on the foot of the wearer.

7. In combination in a shoe fastener, hooks 45 pivotally connected with the shoe upper at opposite sides of the opening therein which is closed by the tongue thereof, and a member having a series of spaced upwardly-bowed portions secured to said tongue, said portions being selectively engageable by said hooks to fasten the shoe on the foot of the wearer.

8. In combination in a shoe fastener, a piece 50 of spring wire bent upon itself to provide members which may be flexed toward and away from each other, said wire being secured to the shoe upper by a strip secured to the upper on the inside thereof bounding the opening in the upper which is closed by the usual tongue, a hook pivotally connected with each of said members, the upper being cut away for this purpose, and means on said tongue which may be engaged by said hooks subject to the flexing of said members toward each other, said members having a normal tendency to flex away from each other to retain said hooks engaged with said means to thus fasten the 55 shoe on the foot of the wearer.

9. In combination in a shoe fastener, a piece 60 of spring wire bent upon itself to provide members which may be flexed toward and away from each other, said wire being secured to the shoe upper by a strip secured to the upper on the inside thereof bounding the opening in the upper which is closed by the usual tongue, a hook pivotally connected with each of said members, the upper being cut away for this purpose, and eyes on said 65 tongue which may be engaged by said hooks, subject to the flexing of said members toward each other, said members having a normal tendency to flex away from each other to retain said hooks engaged with said eyes to thus fasten the 70 shoe on the foot of the wearer.

10. In a shoe fastener, the combination with the shoe upper and tongue, of flexible means applied to said upper having a normal tendency to urge apart the portions of the upper at the 75 opening closed by said tongue, and coacting means on said tongue and the first means engageable subject to the flexing of said first means to fasten the shoe, and said coacting means being disengageable subject to the flexing of said first means to unfasten the shoe.
